UNITED STATES PATENT OFFICE.

WILLIAM WESLEY WOODS, OF SPRINGFIELD, MISSOURI.

COOKING RANGE.

Application filed September 6, 1924. Serial No. 736,323.

To all whom it may concern:

Be it known that I, WILLIAM WESLEY Woods, a citizen of the United States, residing at Springfield, in the county of Greene and State of Missouri, have invented new and useful Improvements in Cooking Ranges, of which the following is a specification.

This invention relates to cooking ranges, and has for its primary object the provision of a range so constructed as to utilize a large portion of the heat which is normally wasted.

A further object of the invention is to provide means for conducting and directing heat generated by the front burners of the range so that it becomes effective to heat the back plates and the oven, whereby it is possible to cook on the back part of the stove with only the two front burners lighted.

With these and other objects in view, which will become apparent as the description proceeds, the invention consists in the novel features of construction, combination of elements and arrangements of parts hereinafter to be fully described and claimed.

In the accompanying drawing forming a part of this specification:—

Figure 1 is a perspective view of a cooking range embodying the invention, a portion of the top being broken away to disclose details of construction;

Figure 2 is a fragmentary vertical sectional view of a portion of the range; and

Figure 3 is an enlarged detail view partly in section of the heat conducting and directing flue.

Referring to the specific illustrative embodiment of the invention illustrated in the accompanying drawing, wherein like reference numerals refer to similar parts through the several views, the cooking range 1 includes suitable legs 2, and set on the legs is a substantially rectangular base 3, upon a portion of which is supported the broiling oven 4, and the baking oven 5. The oven walls are of double formation to provide an air space 6, between the outer wall 7 and the lining 8, which extends entirely around the sides, back and top of the oven. The back wall 9 is of the same length as the base 3 and extends a short distance above the top of the oven. Supported by the oven side wall 7, the back wall 9 and end wall 10, is the solid top plate 11 which overlies the heating elements or burners (not shown)

which are operatively connected to the gas supply pipe 12 and valve 13 in the usual manner. Apertures 14 are provided in the top 11 directly over the front and rear burners to receive the removable plates or covers 15 which may be either of the solid or open skeleton type.

As thus far described, no claim is made thereto. The invention is concerned with a back flue 16, which comprises a comparatively large tube 17 (about two inches in diameter), having one of its ends permanently closed by cap 18 fitting tightly thereon, and secured by brackets or hangers 19 to the underside of top 11 adjacent the rear of the back plates 15. A plurality of alined openings 20 are provided on the front side of the tube 17, and the open upturned end 21 of the tube extends through the wall 7 into the air space 6. Collar 22 secured around the periphery of aperture 23 in the top wall 24 of the oven 5 is provided for connecting the range by a pipe to the flue of the house in which it is installed, in order to obtain sufficient draft to insure the desired circulation of heated air within the range.

In the practice of the invention, it has been found that the use of the two front burners of the range in the usual cooking operations, soon heats the rear plates or covers, by reason of the draft through the back flue 16 and air space 6, so that the back part of the stove may be used for cooking without lighting the back burners. The burning of the front burners due to the direction of the surplus heat by the back flue into the space 6 will also heat the baking oven under ordinary conditions to about 160 degrees Fahrenheit, and maintain it at that temperature as long as the burners are lighted, and this without the use of the oven burners.

It will thus be seen that this construction whereby the heat from the front burners is drawn directly under the rear plates into the back flue, and is then directed into the air space 6 about the oven lining, will greatly decrease the amount of fuel necessary to carry on a given amount of cooking, as it is usually impossible to prepare a complete meal with only two burners.

What is claimed is:—

1. The combination with a cooking range including burners, a top plate overlying said burners, and a double walled oven, of an apertured flue arranged beneath said plate

in rear of the front burners, with the apertures in said flue facing said burners so as to conduct the heat therefrom, the inner open end of said flue discharging into the space between the walls of said oven, the other end of the flue being closed.

2. The combination with a cooking range, having burners, and a top plate overlying the burners, of a perforated tube supported beneath said plate, with the perforations facing the front burners so as to conduct the heat therefrom.

3. The combination with a cooking range

including burners, a top plate overlying said burners, and an oven having double walls, of a tube having spaced apertures in its front side facing the front burners and supported beneath said plate at the rear, means for closing one end of said tube, its other end being open and upturned and discharging between the walls of the oven.

In testimony, that I claim the foregoing as my own, I have hereto affixed my signature.

WILLIAM WESLEY WOODS.
